US00D499702S

(12) **United States Design Patent** (10) Patent No.: **US D499,702 S**
Abe (45) Date of Patent: **** Dec. 14, 2004**

(54) **REMOTE CONTROLLER FOR IMAGE SERVER**

(75) Inventor: **Toru Abe**, Hyogo (JP)

(73) Assignee: **Matsushita Electric Industrial Co., Ltd.**, Osaka (JP)

(**) Term: **14 Years**

(21) Appl. No.: **29/200,742**

(22) Filed: **Mar. 2, 2004**

(30) **Foreign Application Priority Data**

Dec. 22, 2003 (JP) 2003-037746

(51) **LOC (7) Cl.** **14-03**

(52) **U.S. Cl.** **D13/168**

(58) **Field of Search** D14/174, 217, D14/218, 137-139, 151, 191-193, 299, 167, 168; D13/168, 162-164; D21/512-517, 566; D10/104, 106; 455/352-355, 151.1-151.4, 128, 347, 90.3; 348/114, 734

(57) **CLAIM**

The ornamental design for a remote controller for image server, as shown and described.

DESCRIPTION

FIG. 1 is a top perspective view of a remote controller for image server of the present invention;

FIG. 2 is a front view thereof;

FIG. 3 is a rear view thereof;

FIG. 4 is a top view thereof;

FIG. 5 is a bottom view thereof;

FIG. 6 is a first side view thereof; and,

FIG. 7 is a second side view thereof.

1 Claim, 4 Drawing Sheets

FIG. 1

FIG. 2

FIG. 3

FIG. 4

FIG. 5

FIG.6

FIG. 7
